H. A. DOUGLAS

CIRCUIT CONTINUING DEVICE

Filed Nov. 17, 1927

Fig. 1.

Fig. 2.

Inventor:
Harry A. Douglas
By G. H. Gray Atty.

UNITED STATES PATENT OFFICE.

HARRY A. DOUGLAS, OF BRONSON, MICHIGAN.

CIRCUIT CONTINUING DEVICE.

Application filed November 17, 1927. Serial No. 233,876.

My invention relates to circuit continuing devices and has a number of objects and advantages in view.

The device of my invention is inclusive of a spring barrel, a plunger contact projecting through an opening formed through an end of the spring barrel, spring means within said spring barrel for pressing said plunger contact outwardly to yieldingly maintain it in place, and a basket or carrier receiving said spring barrel and contact lengthwise thereof, the end of the basket adjacent the outer end of said contact being formed with a plug receiving socket that is angular to said spring barrel and into whose interior the outer end of the plunger contact extends to be engageable by a plug inserted within said socket.

My invention, in one of its embodiments, is particularly adapted for use as a junction device for electrically and mechanically connecting circuit wires and when the invention is embodied for such use, the spring barrel has an opening through each of its ends and there is a plunger contact projecting through each opening, while the basket or carrier is formed with sockets at its ends or otherwise provided with sockets which are abreast and are open at their nearest sides, the outer ends of the plunger contacts being spring pressed into the interiors of said sockets in position to be engageable by wire terminal plugs inserted within said sockets. The basket desirably has an ear formation which laps the spring barrel and holds it against the bottom of the basket. The basket is also desirably provided with a mounting stem which, when applied to a mounting, serves to hold the ends of the basket tightly upon such mounting to prevent the basket from being turned from the position selected therefor.

The invention will be more fully explained in connection with the accompanying drawing in which Fig. 1 is a perspective view illustrating two circuit continuing devices as they may be employed for placing an automobile horn in circuit; Fig. 2 is a view in elevation of the circuit continuing devices shown in Fig. 1, connecting plugs being shown in section in one of these devices, the plugs being absent in the other device; Fig. 3 is a sectional view on line 3—3 of

Fig. 2; and Fig. 4 is a sectional view on line 4—4 of Fig. 3.

The invention will be first more particularly described in connection with Figs. 2, 3 and 4. The basket is preferably formed of sheet metal and is so shaped as to provide sockets 1 and 2 at its ends and which sockets are sufficiently spaced apart to receive a metal spring barrel 3 therebetween, this barrel having metallic plunger contacts 4 and 5 projecting through the ends thereof and being arranged, together with these contacts, along the bottom of the basket. Ears 6 are struck from the sides of the basket and lap the barrel and serve to hold the barrel tightly against the bottom of the basket. The sockets 1 and 2, which are thus abreast and laterally spaced apart, have lateral openings 7 and 8 through their nearest sides. The metallic coiled spring 9 is placed between the contacts 4 and 5 and presses the outer ends of these contacts through the contiguous openings in the spring barrel and into the bores of the sockets whereby said contacts 4 and 5 are engageable by connecting plugs 10 and 11, these plugs having annular grooves 12 which receive the outer ends of the contacts 4 and 5 that are thus adapted to hold the plugs in place to bring them and the wires of which they constitute terminals into electrical connection.

The basket is provided with a mounting stem 13 which is preferably separately formed therefrom and which passes through the bottom of the basket and through a mounting block 14, the mounting stem being preferably in the form of a rivet which is riveted against the interior surface of the basket bottom and against the mounting block. The portion 15 of the basket that is adjacent the stem is, before the basket is mounted, preferably not as deep as the ends of the basket, the basket portion 15 being forced against the mounting block 14 when the stem 13 is riveted in place whereby the bottom portions 16 of the basket which are desirably coaxial, are tightly held against the mounting block 14 whereby the basket is prevented from being turned.

To prevent short circuiting, a strip of insulation 17 may be placed on the back of the block 14. The mounting block 14, in

automobile practice, is mounted either on the chassis or on the body so that the various circuit wires may be quickly snapped into electrical and mechanical assembly, as illustrated in Fig. 1, for example.

Changes may be made without departing from the invention.

Having thus described my invention, I claim:

1. In a circuit continuing device, the combination with a spring barrel having openings through its ends; of plunger contacts projecting through said openings; spring means within said spring barrel for pressing said plunger contacts outwardly to yieldingly maintain them in place; and a basket receiving said spring barrel and contacts lengthwise thereof and having an ear formation that laps and holds the barrel in place the ends of the basket being formed with plug receiving sockets that are angular to said spring barrel and into whose interiors the outer ends of the plunger contacts respectively adjacent thereto extend to be engageable by plugs inserted within said sockets.

2. In a circuit continuing device, the combination with a spring barrel having openings through its ends; of plunger contacts projecting through said openings; spring means within said spring barrel for pressing said plunger contacts outwardly to yieldingly maintain them in place; and a basket receiving said spring barrel and contacts lengthwise thereof, the ends of the basket being formed with plug receiving sockets that are angular to said spring barrel and into whose interiors the outer ends of the plunger contacts respectively adjacent thereto extend to be engageable by plugs inserted within said sockets.

3. In a circuit continuing device, the combination with a spring barrel; of a plunger contact projecting through an opening formed through an end of the spring barrel; spring means within said spring barrel for pressing said plunger contact outwardly to yieldingly maintain it in place; and a basket receiving said spring barrel and contact lengthwise thereof and having an ear formation that laps and holds the barrel in place, the end of the basket adjacent the outer end of said contact being formed into a plug receiving socket that is angular to said spring barrel and into whose interior the outer end of the plunger contact extends to be engageable by a plug inserted within said socket.

4. In a circuit continuing device, the combination with a spring barrel; of a plunger contact projecting through an opening formed through an end of the spring barrel; spring means within said spring barrel for pressing said plunger contact outwardly to yieldingly maintain it in place; and a basket

receiving said spring barrel and contact lengthwise thereof, the end of the basket adjacent the outer end of said contact being formed into a plug receiving socket that is angular to said spring barrel and into whose interior the outer end of the plunger contact extends to be engageable by a plug inserted within said socket.

5. In a circuit continuing device, the combination with a spring barrel having openings through its ends; of plunger contacts projecting through said openings; spring means within said spring barrel for pressing said plunger contacts outwardly to yieldingly maintain them in place; a basket receiving said spring barrel and contacts lengthwise thereof and having an ear formation that laps and holds the barrel in place, the ends of the basket being formed with plug receiving sockets that are angular to said spring barrel and into whose interiors the outer ends of the plunger contacts respectively adjacent thereto extend to be engageable by plugs inserted within said sockets; a mounting stem upon and projecting outwardly from the bottom of the basket; and a mounting to which said stem is secured and upon which the stem tightly holds the bottom of the basket at the end of the basket.

6. In a circuit continuing device, the combination with a spring barrel having openings through its ends; of plunger contacts projecting through said openings; spring means within said spring barrel for pressing said plunger contacts outwardly to yieldingly maintain them in place; a basket receiving said spring barrel and contacts lengthwise thereof, the ends of the basket being formed with plug receiving sockets that are angular to said spring barrel and into whose interiors the outer ends of the plunger contacts respectively adjacent thereto extend to be engageable by plugs inserted within said sockets; a mounting stem upon and projecting outwardly from the bottom of the basket; and a mounting to which said stem is secured and upon which the stem tightly holds the bottom of the basket at the ends of the basket.

7. In a circuit continuing device, the combination with a spring barrel; of a plunger contact projecting through an opening formed through an end of the spring barrel; spring means within said spring barrel for pressing said plunger contact outwardly to yieldingly maintain it in place; a basket receiving said spring barrel and contact lengthwise thereof and having an ear formation that laps and holds the barrel in place, the end of the basket adjacent the outer end of said contact being formed into a plug receiving socket that is angular to said spring barrel and into whose interior the outer end of the plunger contact extends to be engageable by a plug inserted within

said socket; a mounting stem upon and projecting outwardly from the bottom of the basket; and a mounting to which said stem is secured and upon which the stem tightly holds the bottom of the basket at an end of the basket.

8. In a circuit continuing device, the combination with a spring barrel; of a plunger contact projecting through an opening formed through an end of the spring barrel; spring means within said spring barrel for pressing said plunger contact outwardly to yieldingly maintain it in place; a basket receiving said spring barrel and contact lengthwise thereof, the end of the basket ad-

jacent the outer end of said contact being formed into a plug receiving socket that is angular to said spring barrel and into whose interior the outer end of the plunger contact extends to be engageable by a plug inserted 20 within said socket; a mounting stem upon and projecting outwardly from the bottom of the basket; and a mounting to which said stem is secured and upon which the stem tightly holds the bottom of the basket at an 25 end of the basket.

In witness whereof, I hereunto subscribe my name.

HARRY A. DOUGLAS.
